UNITED STATES PATENT OFFICE.

JOHN H. LEE HOLCOMBE, OF THE UNITED STATES NAVY.

DESIGN FOR A BADGE.

SPECIFICATION forming part of Design No. 29,054, dated July 19, 1898.

Application filed June 2, 1898. Serial No. 682,405. Term of patent 7 years.

To all whom it may concern:

Be it known that I, JOHN HITE LEE HOLCOMBE, a citizen of the United States, a lieutenant in the United States Navy, serving on 5 board the United States steamship *Adams*, stationed at Mare Island, California, have invented and produced a new and original Design for a Badge; and I do hereby declare the following to be a full, clear, and exact description of the invention, such as will enable others skilled in the art to which it appertains to make and use the same.

My design consists, essentially, of a circular badge having a central light-colored ground 15 with the representation of the American flag displayed centrally thereon, said light-colored ground having an irregular outline shaded into a darker or contrasting border, the shading being composed entirely of radial lines 20 having for their center the center of the badge, the effect being that of strong rays of light radiating from the flag as the center of illumination in front of a dark background.

My design also embodies a dark unshaded 25 circular surrounding border of a uniform

width, except at the bottom of the badge, where the said border encroaches inwardly upon the shaded border of the central ground, as shown in the accompanying drawings.

In the accompanying drawings, Figure 1 30 illustrates an enlarged plan view of a button or badge embodying my design, and Fig. 2 represents an elevation of the same.

1 designates the entire head of the badge.

2 designates the central light-colored 35 ground, and 3 the shaded contrasting border of the central ground.

5 designates the unshaded circular surrounding border, widened inwardly at 4, and 6 designates the representation of the American flag spread centrally upon the badge. 40

What I claim as my invention is—

The design for a badge, substantially as herein described and shown.

In testimony whereof I affix my signature 45 in presence of two witnesses.

J. H. LEE HOLCOMBE.
